UNITED STATES PATENT OFFICE

151,410

DESIGN FOR A LOWER RAIL FOR
VENETIAN BLINDS

Harry S. Rosenbaum, Baltimore, Md.

Application October 24, 1946, Serial No. 134,203

Term of patent 14 years

(Cl. D21—6)

To all whom it may concern:

Be it known that I, Harry S. Rosenbaum, a citizen of the United States, residing at Baltimore, in the State of Maryland, have invented a new, original, and ornamental Design for Lower Rail for Venetian Blinds, of which the following is a specification, reference being had to the accompanying drawing, forming part thereof.

Fig. 1 is a perspective view of a lower rail for Venetian blinds, as shown.

Fig. 2 is a section along line 2—2 of Fig. 1.

Fig. 3 is a fragmental side elevation of the lower rail for Venetian blinds.

I claim:

The ornamental design for a lower rail for Venetian blinds, as shown.

HARRY S. ROSENBAUM.
